Primary Examiner — Paula Greene(74) *Attorney, Agent, or Firm* — Crowell & Moring LLP(57) **CLAIM**

The ornamental design for cable storage in headphones, as shown and described.

DESCRIPTION

This application contains subject matter related to the following co-pending U.S. design patent application:

Application Ser. No. 29/393,296, filed herewith and entitled "Headphones".

FIG. 1 is a front perspective view of cable storage in headphones, in an open position, according to my design;

FIG. 2 is a left perspective view thereof, the right perspective view being mirror symmetrical;

FIG. 3 is a right side view thereof, the left side view being mirror symmetrical;

FIG. 4 is a bottom view thereof;

FIG. 5 is a bottom perspective view thereof; and,

FIG. 6 is a front perspective view thereof, in a closed position. The broken lines are for illustrative purposes only and form no part of the claimed design.
